UNITED STATES PATENT OFFICE.

ALBERT H. FAY, OF WASHINGTON, DISTRICT OF COLUMBIA.

HEADLIGHT DEFLECTOR.

Application filed November 12, 1921. Serial No. 514,735.

To all whom it may concern:

Be it known that I, ALBERT HILL FAY, a citizen of the United States, residing at Washington, in the District of Columbia, have invented certain new and useful Improvements in Headlight Deflectors, of which the following is a specification.

This invention relates to certain new and useful improvements in head lights, such as 10 are used on automobiles, for example, and more particularly stated contemplates the production of a light deflecting means, which will disperse the light free from glare and without reducing or dimming the useful 15 intensity of the light.

Heretofore certain attempts have been made to effectively procure the proper control and distribution of the rays of light projected from head lights so that a maximum 20 amount of the light will be projected forwardly, but in a plane sufficiently low to prevent the intensely annoying glare of the light in one's eyes when approaching the light, or upon being approached by said light. Numerous 25 deflectors as well as various special lenses have been produced in an endeavor to overcome the difficulties now experienced, but these have not proven successful in use 30 for the reason that the intensity of the light has been so reduced in the case of the special lenses, and so restricted in distribution in the case of the deflectors that the usefulness 35 of the light for head light purposes is practically lost.

My present invention has been produced to overcome the disadvantages now found in devices of this character, and has for an 40 object the production of a deflector which can be readily associated with the usual reflector, so as to intercept or interrupt a relatively 45 large portion of the forwardly projected light, and deflect said intercepted light downwardly and forwardly below the horizontal plane of the head light.

Another object of my invention is to produce a light deflecting means formed of relatively deep and properly spaced strips, each having a reflecting surface formed substantially of contiguous straight and curved 50 portions which serve to project the intercepted rays in parallel relation forwardly and toward the ground and in adjacent fan-like relation from the ground to the horizontal plane of the forwardly and uninterrupted projected rays.

A further object of my present invention

is to reduce the glaring effect of the headlight by providing relatively broad or deep deflecting strips suitably spaced proportionately to their depth and capable of interrupting but a portion of the projected rays, and further arranged so that the uninterrupted rays, flowing from the exposed portions of the reflector becomes less intense and finally disappear upon approaching the headlight.

A still further object of my invention is to form and arrange the deflecting strips adjacent the reflector and source of light so that substantially the entire power of the 60 light is controlled without producing a blinding glare and distributed at a utilizable distance in front of the automobile or other device to which the headlight may be applied.

With these and other objects in view my invention further consists in the construction and arrangement of the several parts which I have found to be both convenient and inexpensive to manufacture, and which 75 will more fully be hereinafter pointed out in the specification and claims hereto appended.

In the accompanying drawings wherein I have shown an embodiment of my invention as applied somewhat diagrammatically 80 to a headlight:—

Fig. 1 is a vertical sectional view through a parabolic reflector provided with a source of light, and my improved deflector arranged 85 adjacent thereto, the several paths of reflected and deflected light being shown so as to more clearly understand my invention; and

Fig. 2 is a front view of the deflector.

Referring to the drawings, I have shown my improved deflector associated with a reflector 1 arranged about the source of light 2. The light 2 is adjusted in focus with the reflector so as to obtain the proper projection of the reflected rays as will be understood.

In the present embodiment of my invention I have shown a parabolic reflector from which the rays are projected forwardly 105 in parallel relation to each other. These parallel rays are indicated by the relatively close parallel lines 3 shown in Fig. 1. Some of the light rays proceeding from the source of light 2 and striking the reflector are indicated by the radiating lines 4.

My light deflecting means is arranged ad-

jacent the reflector 1 and may be secured thereto by a band 5, or in any other suitable manner. It consists of a series of light deflecting strips 6 formed of metal or any other appropriate opaque material, the under side or face of which is treated to form a reflecting surface 7. The upper faces of the strips are preferably non-reflecting, and may be painted or enameled for example 10 any color from a dead black to a bright white.

The several strips 6 are arranged relatively close to each other, but are spaced apart sufficiently far to permit a relatively 15 large portion of the reflected light to pass forwardly unobstructed. The remaining portion of light is intercepted by these strips 6 and deflected and distributed in a manner to be presently described.

20 The construction and arrangement of the deflecting strips or elements 6 are important factors in effecting the objects of my invention. As shown the strips are of a depth substantially equal to the depth of the reflector, and are arranged in parallel and 25 slanting relation outside of and adjacent to the reflector. The spacing between the strips may be about one-third the depth or length thereof, as shown, but this relative 30 proportion can be varied so as to bring the strips much closer together, and I do not limit myself to this exact disclosure.

The herein shown angular or inclined disposition of the strips I have found to be effective in that a major portion of the total reflected light is deflected downwardly and forwardly and the balance of said light is allowed to proceed between the spaced strips uninterrupted. The additional advantage 40 obtained from my present inclined arrangement of wide or deep deflecting strips is that at a given distance of approach, say twenty-four feet, for example, the exposed portions of the parabolic reflector are entirely hidden from view. At distances 45 greater than the above example, the glaring effect is greatly diminished and has been found to be unobjectionable.

In order to obtain a maximum reflection 50 of the light forwardly and at the same time reduce to a minimum the glare upon approach, I have found that the angle at which the strips should be set, should be proportional to the depth of the strips and 55 the quantity of light not intercepted.

The deflection of the intercepted rays will now be described in conjunction with the specific form of reflecting surface provided upon the under face of the strips 6.

60 In order to deflect a portion of the rays upon the ground substantially near the automobile and at the same time deflect the remaining portions of the total deflected rays forwardly at a relatively long distance below 65 the horizontal plane of the headlight,

I provide a deflecting surface upon each strip consisting substantially of a straight portion 8 and a curved portion 9, said portions being contiguously associated as shown. The straight or plane surface 8 is 70 of a size to permit a maximum deflection of a portion of the intercepted rays clear of the end of the adjacent strip. The rays deflected by this straight surface are indicated at 10 and as shown proceed in a downward and parallel direction immediately in 75 front of the automobile.

The curved portion 9 of the deflecting surface receives the remaining portion of the intercepted rays, and deflects them in 80 a fan-like manner between the aforesaid parallel rays striking the ground and the forwardly projected uninterrupted horizontal rays. These rays are indicated by the numeral 11 and as will be seen are sent forwardly a substantially long distance, the 85 uppermost of said rays merging into and passing along with the uninterrupted rays to infinity or the vanishing point of the reflected light.

90 The straight surface 8 as shown in the present embodiments of my invention is tangent to the curved surface 9, said surfaces meeting at a point P in such a manner that the end or point of the tangent is the 95 point of the deflection curve, which in the disclosure herein is the arc of a circle. From the point P the intercepted parallel rays are gradually spread out and merged with the straightforward rays. I prefer to proportion 100 the deflection so that about one-half of the intercepted rays are deflected from the plane 8 or up to the point P and the remainder are deflected and dispersed from the curved surface 9.

105 The relation of the plane 8 and curved surface 9 may be varied. Likewise the form, size and arrangement of each may be changed. For example, the curve 9 may be hyperbolic, parabolic, or otherwise. In some cases the plane surface may be used without being tangent to the curved surface, that is various relations of curved and straight surfaces may be provided to effect 110 the projection of a maximum number of rays with the least possible glare.

In my present invention the deflecting strips are arranged outside of the reflector and designed with a view to obtaining a maximum distribution of the total reflected light at a utilizable distance from the headlight, and at the same time reduce to a minimum the glare now incident to any long and upward projection of the rays upon approaching the headlight.

115 It will be seen that the intermediate strip 13 is positioned so that the axis of the parabolic reflector is tangent to the deflecting surface. From this location I position the strips above and below so as to obtain the 120 130

reflection and deflection as heretofore described.

In practice the deflecting strips 6 are suitably held within an encircling frame or band 12, into which projecting tangs, for example, of the strips may be secured by brazing or otherwise. I do not limit myself to any particular way of arranging and holding the deflecting strips adjacent the reflector.

I prefer to affix a lens of clear glass adjacent the reflector as shown in dotted lines and secure same in position in any approved manner.

15 I claim:

1. In a headlight, the combination with a reflector of a source of light, and means for interrupting a major portion of the forwardly projected rays, said means involving 20 contiguous substantially straight and curved reflecting surfaces, whereby the portion of said rays deflected from each straight surface strikes the ground relatively close to said headlight, and the remaining portion of 25 the interrupted rays deflected from each curved surface is merged into and sent forwardly with the uninterrupted forwardly projected rays.

2. In a headlight the combination with a 30 reflector of a source of light, and means including a plurality of relatively deep strips for interrupting a large portion of the forwardly projected rays and deflecting said portion so that substantially one-half of the 35 interrupted rays strike the ground relatively close to said headlight, and the other half of said rays is merged into and deflected forwardly with the uninterrupted forwardly projected rays, said strips being spaced relatively close to one another and each having 40 a substantially straight and a curved portion.

3. A deflector for headlights comprising a 45 series of strips having a reflecting surface upon the under face thereof, said surfaces being formed of substantially straight and curved portions horizontally arranged with respect to the longer dimension of each of

said strips to intercept relatively large portions of reflected light and deflect the same 50 forwardly in a relatively large plane below the horizontal.

4. A deflector for headlights comprising a series of strips of material having a reflecting surface upon one face thereof, said surface being formed of substantially contiguous and approximately straight and curved portions arranged horizontally to intercept a relatively large portion of reflected light and deflect the rays thereof 60 from the aforesaid straight portion in parallel relation to each other and the rays of said light from the aforesaid curved portion in fan-like relation to each other adjacent the aforesaid parallel rays.

5. In a headlight, the combination with a reflector, of a source of light, and means for interrupting a portion of the forwardly projected rays including relatively deep and spaced apart strips each having a slightly 70 curved and adjacent approximately straight reflecting surface for merging the deflected rays into the forwardly projected rays below the horizontal, said curved and straight surfaces of each strip being disposed horizontally 75 with respect to the longer dimension thereof.

6. In a headlight, the combination with a reflector, and a source of light, and means including a plurality of transverse thin relatively wide plates having substantially curved and straight surfaces substantially along the axis of the reflector for interrupting a large portion of the forwardly projected rays, the plates being spaced apart 80 so that a portion of the interrupted rays striking said straight surfaces is deflected downwardly and strikes the ground relatively close to the headlight, and the portion of the interrupted rays striking the 85 curved surfaces is deflected forwardly and downwardly and merged into the uninterrupted forwardly projected rays.

In testimony whereof I affix my signature.

ALBERT H. FAY.
